DESIGN FOR A COMBINED BOTTLE AND STOPPER

Paul H. Ganz, New York, N. Y.

Application April 27, 1936, Serial No. 62,323

Term of patent 14 years

To all whom it may concern:

Be it known that I, Paul H. Ganz, a citizen of the United States and a resident of the city, county, and State of New York, have invented a new, original, and ornamental Design for a Combined Bottle and Stopper, of which the following is a specification, reference being had to the accompanying drawing, forming part thereof.

Figure 1 is a perspective view of my combined bottle and stopper, showing my new design;

I claim:

The ornamental design for a combined bottle and stopper, as shown and described.

PAUL H. GANZ.
